(57) **CLAIM**

The ornamental design for a clip and belt assembly, as shown and described.

DESCRIPTION

FIG. 1 is a right side elevation view of a clip and belt assembly, showing my design.

FIG. 2 is a top plan view thereof.

FIG. 3 is a left side elevation view thereof.

FIG. 4 is a bottom plan view thereof.

FIG. 5 is a front elevation view thereof.

FIG. 6 is a rear elevation view thereof.

FIG. 7 is a front perspective view thereof.

FIG. 8 is a perspective view of the clip and belt assembly in use thereof.

FIG. 9 is a perspective view thereof in use; and,
FIG. 10 is another perspective view thereof in use.

The broken lines on the shaded surfaces of the claim depict stitching that forms no part of the claimed design. The broken lines outside of the claim of FIGS. 8-10 depict environmental structure that forms no part of the claimed design.

1 Claim, 10 Drawing Sheets
